(57) **CLAIM**

The ornamental design for a bottle, as shown and described.

DESCRIPTION

FIG. 1 is a perspective view of a bottle, embodying our new design;

FIG. 2 is a top planar view thereof;

FIG. 3 is a front elevational view thereof, the back being a mirror image thereof; and,

FIG. 4 is a right side elevational view thereof.

The broken line showing of the environment is for illustrative purposes only and forms no part of the claimed design.
